UNITED STATES PATENT OFFICE

ABRAHAM N. SPANEL AND MAXWELL ROBITAILLE, OF ROCHESTER, NEW YORK, ASSIGNORS TO VACUUMIZER MANUFACTURING CORPORATION, OF ROCHESTER, NEW YORK, A CORPORATION OF NEW YORK

DESIGN FOR A SOAP DISH

Application filed July 3, 1930. Serial No. 36,272. Term of patent 14 years.

To all whom it may concern:

Be it known that we, ABRAHAM N. SPANEL and MAXWELL ROBITAILLE, citizens of the United States, residing at Rochester, in the county of Monroe and State of New York, have invented a new, original, and ornamental Design for Soap Dish, of which the following is a specification, reference being had to the accompanying drawing, forming part thereof.

In the drawings:

Figure 1 is a top plan view of the soap dish.

Figure 2 is a side elevation of the soap dish showing my new design.

I claim:

The ornamental design for a soap dish as shown.

In testimony whereof we affix our signatures.

ABRAHAM N. SPANEL.
MAXWELL ROBITAILLE.
